LUBRICANT CONTROL MECHANISM

Filed Nov. 11, 1929

UNITED STATES PATENT OFFICE

JOSEPH W. LOVELL, OF DETROIT, MICHIGAN

LUBRICANT CONTROL MECHANISM

Application filed November 11, 1929. Serial No. 406,365.

My invention relates to a new and useful improvement in a lubricant control mechanism adapted for use on electrically controlled or electrically driven machinery and engines, and has for its object the provision of means for prevention of operation without sufficient lubricant.

It is an other object of the present invention to provide a device which will control the operation of the engine dependent upon the amount of lubricant present in the lubricant container.

Another object of the invention is the provision of a device of this class which will be simple in structure, economical of manufacture, highly efficient in use, and compact in form.

Other objects will appear hereinafter.

The invention consists in the combination and arrangement of parts hereinafter described and claimed.

The invention will be best understood by a reference to the accompanying drawing which forms a part of this specification, and in which:

Fig. 1 is a central vertical sectional view of the invention.

Fig. 2 is a diagrammatic view of the wiring used in the invention.

Fig. 3 is a fragmentary sectional view of a modified form of the invention.

Fig. 4 is a diagrammatic view of the wiring used in the modified form.

In the invention I provide a lubricant container 7, having a filling spout 8, provided with a closure 9. An outlet nipple 10 is formed on bottom 11 of the container 7 to which may be attached suitable pipes leading to various parts of the machine to be lubricated. The valve head 12 is used as a closure for the outlet part of the container 7 and a stem 13 which projects upwardly from valve head 12 extends through a guide sleeve 14, which is securely fastened to a partition or top 15, through which it extends. The lock nut 16 serves to clamp the flange 17 on the partition or top 15. A washer 18 is positioned in embracing relation on the valve stem 13 and is engaged by one end of the spring 19, the opposite end of which engages

the valve head 12 and serves to normally retain the valve head in closing position. A link 20 pivotally connects the upper end of valve stem 13 to one end of rockable arm 21, which is connected by link 22 formed from insulating material to the core leg 23, the opposite leg 24 extending through the magnetic coil 25 and operating as a core therefor. This core is secured to the plate of insulation 26 which is attached to the top or partition 15 by means of the rods 27. The construction is such that when the magnetic coil 25 is energized, the valve head 12 will be lifted from its seat so that the lubricant can flow through the nipple 12 into the various pipes which may be attached thereto.

Projecting through the top or partition 15 is a guide sleeve 28 which is secured to the partition or top 15 by the nut 29 which clamps the flange 30 on the top or partition 15. Slidably projected through the guide sleeve 28 is a rod 31 which is attached to a float 32 positioned in the container 7. Rockably mounted on the upper end of rod 28 is a disc 33 of insulating material carrying on its upper surface the circular metallic contact ring 34 adapted when the float 32 is raised in container 7 to engage the terminals or contacts 35 and 36 and close the circuit through these terminals or contacts. These terminals or contacts are mounted on a bracket 37 of insulating material, which is supported on the top or partition 15. A cover 38 is mounted on the container 7 to enclose the mechanism positioned above the container.

In operation, when it is desired to start the machinery or engine with which the invention is used, the starter switch 39 is moved to a closing position so as to close the circuit between the contacts 40 and 41. The contact 41 is connected by the wire 42 to the contact 43 and through the wire 44 to the contact 45 to which is attached the feed wire 46. The contact 40 is connected by the wire 47 to the contact 36 and the contact 35 is connected by the wire 48 to the magnetic coil 25. This coil is connected by the wire 49 to the contact 50 which connects to the feed wire 51 and through the circuit breaker 52 to

the magnetic coil 53, which is used to operate the main switch controlling the machine or engine. The contact 35 is connected by the wire 55 through the circuit breaker 54 to the coil 53. The coil 56 controlling the circuit breaker 54 is connected by the wire 57 to the machine or engine 60. A wire 61 connects through the coil 62, which controls the circuit breaker 52, and the wire 63 to the contact 64. The wire 65 connects the motor 60 to the contact 66. The contact 67 of the stop switch 68 is connected by the wire 69 to the contact 43.

When the switch 39 is closed and a sufficient quantity of lubricant is in the container 7, the float 32 will be risen to a height sufficient to close the circuit between the contacts 36 and 35, thus closing the circuit to the magnetic coil 25 which will effect the movement of valve head 12 from its seat. The circuit to the coil 25 will be through the wires 51 and 49 and through the wires 48, switch 34, switch 39, wire 42, contact 43, wire 44, contact 45 and wire 46. At the same time the circuit to the magnetic coil 53 will be closed and this coil energized. The circuit to this coil will be through wires 51, contact 50 and circuit breaker 52 and through the circuit breaker 54, wire 55, switch 34, wire 47, switch 39, wire 42, contact 43, wire 44, contact 45 and wire 46. When the magnetic coil 53 is energized, the main control switch will be moved to closed position, thus connecting the feed wire 46, because of the movement of the blade 70 into closing position, through the contact 71 and the contact 58 and the wire 57 and coil 56 and wire 59 to the motor 60. At the same time through engagement of the contact arm 72 with the contact 43, the circuit will be established through the contact 43 and the contact 72 and the wire 69 to the magnetic coil 25. At the same time the feed wire 51 will be connected through the contact arm 73 and the wire 65 to the motor 60. The feed wire 74 will also be connected through the contact 75, the contact arm 76, the wire 63 and the coil 62 to the motor 60.

It is thus seen that when the switch 39 is closed and there is sufficient lubricant in container 7 to maintain the float 32 elevated so that the contact ring 32 engages contacts 35 and 36, the lubricant will be released for flowing to the machine and the switch which controls the machine's operation will be closed. Should there not be sufficient lubricant in the container 7 to elevate the float 32 a sufficient distance for bringing about the engagement between the contact ring 34 and the contacts 35 and 36, the circuit to the coil 25 would not be closed, as clearly appears from the diagrammatical view so that the coil 53 would not be energized and a starting of the machine would not be effected. In this way there is assured a prevention of the op-

eration of the machine unless the lubricant is proper.

In Fig. 3 I have shown the modified form of the structure for use on machines which require more power for their operation than machines with which the form shown in Fig. 1 would be used. With large machines or motors, large magnetic switches are used for their control and the form shown in Fig. 3 and Fig. 4 illustrates the use of the invention whereby a switch may be incorporated with the magnetic arm so as to permit the flow of sufficient amperage to the switch operating magnetic coil to properly energize it. The structure shown in Fig. 3 is similar to that already described excepting that an insulating block 85 is secured to the arm 21 and provided with a contact 86 connected to the cable 87. This contact 86, when the arm 21 is rocked upwardly, is adapted to engage the contact 88 mounted on rod 89 which is slidably mounted in the lugs 90 which project outwardly from the blade 91 which is mounted on insulating block 92. The rod 89 and the lugs 90, as well as blade 91 are metallic and a cable 93 attaches to the blade 91.

The link 20 connects the valve stem 13 to the arm 21 in the manner described for Fig. 1 and the contacts 35 and 36 are engageable with the contact ring 34 which is moved upwardly and downwardly as the rod 31 is moved upwardly and downwardly so that the float switch is still retained as shown in Fig. 4, in operation when the starting switch 39 is closed so as to establish connection between the contacts 41 and 40 and the float switch 34 has closed the circuit between the contacts 35 and 36, the feed wire 46 will, through the contacts 45, wire 44, contact 43 and wire 42, be connected to the magnetic coil 25 through the wire 48. The feed wire 51 is connected by means of the wire 49 to the magnetic coil 25 so that the magnetic coil 25 would thus be energized to rock the arm 21 and bring the contact 86 into engagement with the contact 88. The cable or wire 87 connects the contact 86 with the contact 36 and the cable or wire 93 connects the contact 88 through the circuit breaker 54 to the magnetic coil 53 to which the feed wire 51 is connected through the circuit breaker 52. Thus the circuit to the magnetic coil 53 would be made without passing through the magnetic coil 25 as would be required in the form shown in Fig. 1. This permits the use of the device on machines of larger dimensions, having larger magnetic coil for throwing a switch. The remainder of the wiring indicated in Fig. 3 is as already described for Fig. 2.

The advantages with the use of the form shown in Fig. 3 are the same as are shown in Fig. 1.

While I have illustrated and described the preferred form of construction, I do not wish

to limit myself to the precise details of the structure shown but desire to avail myself of such variations and modifications as come within the scope of the appended claims.

5 Having thus described my invention, what I claim as new and desire to secure by Letters Patent is:

1. A lubricant control mechanism of the class described, adapted for use with a machine having an electrically operated control and electric means for operating said control, comprising: a lubricant container; a float in said container; a valve for controlling flow of lubricant from said container; 10 electromagnetic means operable upon being energized for moving said valve to open position; an electric circuit connecting to said electro-magnetic means; a switch interposed in said circuit and normally held closed by 15 said float and opened upon the movement of said float downwardly in said container to a pre-determined distance; and a circuit leading to said electric means, said circuit being passed through said float operated switch.

25 2. In a device of the class described, a **U** shaped electromagnet core; an arm rockably mounted at one end on one of the legs of said core and adapted, upon the energizing of said magnet, for rocking upwardly; a container 30 positioned below said magnet having an outlet opening formed in its base; a valve for closing said opening; a valve stem connected to said valve adapted upon upward rocking movement of said arm for opening said valve; 35 a contact carried by and insulated from the free end of said arm; and a stationary contact engageable with said contact mounted on said arm upon energizing of said magnet.

40 In testimony whereof I have signed the foregoing specification.

JOSEPH W. LOVELL.
